UNITED STATES PATENT OFFICE

102,075

DESIGN FOR A COMBINATION TAIL AND SIGNAL LIGHT

Branny Bleczinski, Methuen, Mass.

Application September 22, 1936, Serial No. 64,964

Term of patent 14 years

To all whom it may concern:

Be it known that I, Branny Bleczinski, a citizen of the United States, residing at Methuen, in the county of Essex and State of Massachusetts, have invented a new, original, and ornamental Design for a Combination Tail and Signal Light, of which the following is a specification, reference being had to the accompanying drawing, forming part thereof.

Figure 1 is a view in front elevation of a combination tail and signal light, showing my new design.

Figure 2 is a view in side elevation thereof.

Figure 3 is a top plan view.

I claim:—

The ornamental design for a combination tail and signal light as shown.

BRANNY BLECZINSKI.
